US0D1041315S

(12) **United States Design Patent** (10) **Patent No.:** **US D1,041,315 S**
(45) **Date of Patent:** **** Sep. 10, 2024**

(54) **BOTTLE**

(71) Applicant: **INDUSTRIAS ALEN, S.A. DE C.V.**
Santa Catarina (MX)

(72) Inventor: **Cristina Julieta Castro-Flores**, Santa
Catarina (MX)

(73) Assignee: **INDUSTRIAS ALEN, S.A. DE C.V.**
Santa Catarina (MX)

(**) Term: **15 Years**

(21) Appl. No.: **29/824,688**

(22) Filed: **Jan. 26, 2022**

(30) **Foreign Application Priority Data**

Nov. 3, 2021 (MX) MX/f/2021/003297

(51) **LOC (14) Cl.** **09-01**

(57) **CLAIM**

The ornamental design for a bottle, as shown and described.

DESCRIPTION

FIG. 1 is a perspective view of a bottle showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines depict portions of the bottle that form no part of the claimed design.

1 Claim, 5 Drawing Sheets
